Patented July 6, 1909.

3 SHEETS—SHEET 3.

UNITED STATES PATENT OFFICE.

LANSING ONDERDONK, OF NEW YORK, N. Y., ASSIGNOR TO UNION SPECIAL SEWING MACHINE CO., OF CHICAGO, ILLINOIS, A CORPORATION OF ILLINOIS.

SEWING-MACHINE LOOPER-MOVEMENT.

No. 926,891.

Specification of Letters Patent.

Patented July 6, 1909.

Application filed November 9, 1901. Serial No. 81,765.

To all whom it may concern:

Be it known that I, LANSING ONDERDONK, a citizen of the United States, residing at New York, in the county of New York, State of New York, have invented certain new and useful Improvements in Sewing-Machine Looper-Movements, of which the following is a description, reference being had to the accompanying drawing and to the letters and figures of reference marked thereon.

My invention relates to an improvement in sewing machines, and especially to a looper mechanism therefor.

As herein shown, the invention has been especially intended to provide a looper mechanism for blind stitch sewing machines of the type substantially as shown in Patent No. 721,077—granted Feb. 17, 1903, and shown also in an application filed by me on the 31st day of December, 1901, Serial No. 87,959 but it will be understood that this looper mechanism and the manner of operating the same may be applied to machines other than of the type aforesaid.

The invention consists primarily of a sewing machine looper, coöperating with a needle arranged in a plane reciprocating substantially at right angles thereto, said looper being supported upon a rod fulcrumed in a universal joint, with means for raising and lowering said looper, and imparting to it a lateral movement as it rises and falls, and having also means for bodily oscillating the same in the direction of the length of the looper.

Again, the invention consists in a looper mechanism for blind stitch machines, comprising a looper arranged and operating entirely above the work support, in combination with a needle reciprocating across the line of the seam; also operating above the work support, said looper being mounted upon a universal joint upon which it rocks as it rises and falls, with means also for bodily swinging said universal joint whereby the looper is also swung bodily.

Again, the invention consists in a special construction of looper and in the particular means for imparting the various movements thereto, as hereinafter described and referred to in the appended claims.

The invention is illustrated in the accompanying drawings, in which—

Figure 1 represents a front elevation of so much of a sewing machine as is necessary to

an understanding of my invention; Fig. 2 is a detached view illustrating the mechanism for imparting the various movements to the looper; Figs. 3 and 4 are front views showing the looper and needle at the respective extremes of movement; Figs. 5 to 10 represent in detail the manner of forming the stitch; and Figs. 11 to 13 are respectively front, rear and sectional views of my special form of looper.

In these drawings, A represents the standard of the machine; B the work support, which is provided with a throat plate having a V-shaped ridge or projection C, over which the goods to be sewed are crimped; D represents the overhanging arm or goose-neck; and E as a whole the head of the machine. These parts, together with the transverse driving shaft E, are substantially of the construction shown in the second application above referred to, and as they form no particular part of this invention, need not be more specifically referred to.

To the rear side of the belt wheel F is attached a crank pin 1, upon which is pivoted one end of the pitman rod 2, which, at its opposite end embraces a ball stud 4, upon the crank 5; fixed to the rock shaft 6, journaled in the bearing barrel 7 on the head of the machine. Upon the opposite side of this bearing barrel, and upon the rock shaft is fixed another crank 9, to which is pivotally secured a forked pin or bolt 10. Between the forks of this pin or bolt 10 is pivotally secured the upper end of the looper supporting rod 11, which may be in one piece, or which, as herein shown, comprises the upper part 12 pivoted between the forks, and the lower part 13, screwed into a socket in the upper part.

The shank of the looper 14 is secured in a collar or clamp 15 on the lower end of the rod 13. This rod 13, through the action of the cranks 5 and 9, is raised and lowered to impart to the looper a rise and fall, to enable it to pass from one side the line of the seam to the other, over the apex or ridge on the throat plate, and to enable it to escape obstructions such as seams or extra thicknesses of goods; but to impart this sidewise movement from one side the line of the seam to the other, it is necessary to freely pivot or fulcrum the looper supporting rod, in order that as it rises and falls and the cranks pass from one side the center to the other, the tilting

movement may be imparted, and to this end I have provided the arm 16, enlarged at its outer end and formed with a recess through which the rod 13 passes, this recess being 5 formed to receive and hold a ball bearing 17. In the rise and fall, therefore, of said looper supporting rod, it slides through the ball 17, and at the same time oscillates said ball in its support, whereby the looper has the four 10 motions above referred to. It is also necessary to impart to said looper a forward and backward movement in the direction of its length to enable it to take and leave the needle loop, and also to carry its own loop 15 into position to be engaged by the needle, and to this end the arm 16 at its inner end is fixed upon an upright rock shaft 18, journaled in bearing lugs 19 and 20 on the machine frame. The upper end of this rock 20 shaft 18 has clamped about it one end of a rod or bar 21, which at its opposite end has a ball and pitman connection 22, 23, with an eccentric 24, upon the main shaft. As the shaft revolves, therefore, the vertical rock 25 shaft is oscillated, and the bearing through which the looper rod passes, and in which it is fulcrumed swings from front to rear of the machine, thus imparting to the looper a backward and forward movement in the 30 direction of its length.

As a further and special improvement in a machine of this character, I have provided a special construction of looper, shown in detail in Figs. 11 to 13. This looper is provided with a recess on its under side, as shown at 25, the rear shoulder of this recess forming a projection 26, which, in the movement of the looper engages the thread and holds it in position, so that the needle will 35 pass between the under side of the looper and the looper thread. In other words, the looper carries on its under side a spreader for its own loop, which spreader acts as shown in Figs. 5 to 10 of the drawings, Fig. 5 showing 40 the looper just entering the needle loop; Fig. 6, the looper about one-half way over to the other side of the seam, with the looper thread under the looper. Fig. 7 shows the looper in position preparatory to moving back, before 45 the needle engages the looper thread, the said looper thread having been engaged by the projection upon the under side of said looper. In Fig. 8, the looper is shown as having moved back from the position shown in Fig. 5, with the point of the needle just passing 50 under the looper preparatory to engaging the looper thread. Fig. 9 illustrates a cross section of the looper, the point being cut away, but the looper thread shown in full lines, in 55 this sketch the point of the needle having engaged the looper thread and the looper thread being brought into position by the projection on the under side of the looper. Fig. 10 represents the looper passing back 60 over the goods, back to the path of the needle 65

to position preparatory to again entering the needle loop.

Having thus described my invention, what I claim as new, and desire to secure by Letters Patent, is:—

1. In a sewing machine having a suitable work support, suitable stitch-forming mechanism including a looper, an upright support therefor extending vertically above the work support and pivotally supported intermediate its ends, and means for imparting to said looper support, a bodily vertical movement, a swinging movement on its pivot, and a bodily horizontal movement, whereby the looper is carried bodily vertically, bodily 75 sideways, and bodily in the direction of its length; substantially as described.

2. In a sewing machine having a suitable work support, suitable stitch-forming mechanism including a looper, a vertically arranged rod or bar, to the lower end of which said looper is rigidly secured, a universal joint support for said looper rod intermediate its ends, and connections at the upper end of said looper supporting rod for operating it, 85 to carry the looper bodily vertically, in a sidewise direction and in the direction of its length, said connections including a pivotal suspension for the upper end of said bar or rod; substantially as described.

3. In a sewing machine, stitch-forming mechanism including a looper fulcrumed upon a universal bearing, means for imparting to said looper, a bodily sidewise movement, a vertical movement, and a bodily 100 movement in the direction of its length, said means including a universal pivot for said looper separate from the universal bearing; substantially as described.

4. In a sewing machine, stitch-forming 105 mechanism including a thread-carrying needle and a looper fulcrumed upon a universal bearing, means for imparting to said looper, a bodily sidewise movement, a vertical movement and a bodily movement to take and 110 leave the needle loop, said means including a universal pivot for said looper separate from the universal bearing, and including also means for positively swinging the bearing bodily; substantially as described.

5. In a sewing machine, a looper arranged and operating entirely above the work support, in combination with a needle reciprocating across the line of the seam also operating above the work support, said looper 115 being mounted upon a universal joint, upon which it rocks as it rises and falls with means also for positively swinging said universal joint bodily, whereby the looper is also swung bodily; substantially as described.

6. In a sewing machine, stitch-forming mechanism including a looper, a support therefor, a crank from which the support is pivotally suspended, and a universal bearing 120 in which the supporting rod is fulcrumed, and

means for operating the crank, and means for positively swinging the bearing bodily; substantially as described.

7. In a sewing machine, a looper, a supporting rod therefor, means for operating the same, including a crank from which the supporting rod is pivotally suspended, its pivotal axis being transverse to the axis of oscillation of the crank, a universal bearing in which the supporting rod is fulcrumed, and means for bodily swinging the bearing; substantially as described.

8. In a blind stitch sewing machine, in combination with a needle arranged above the work support and reciprocating across the line of seam, a looper mounted upon a vertical rod pivotally suspended at its upper end from a crank arm, with means for operating said crank arm, a universal bearing in which said rod is fulcrumed, and with respect to which it is vertically movable, and means for swinging said universal bearing bodily; substantially as described.

9. In a blind stitch sewing machine, in combination with a needle arranged above the work support and reciprocating across the line of seam, a looper mounted upon a vertical rod pivotally suspended at its upper end from a crank arm, with means for operating said crank arm, a universal bearing in which said rod is fulcrumed, and with respect to which it is vertically movable, a swinging arm in which said universal bearing is mounted, and means for swinging said arm; substantially as described.

10. In a sewing machine stitch-forming mechanism including a looper mounted upon a swinging universally pivoted support, a rocking crank frame for raising and lowering and swinging said support, a rocking arm supporting a universal pivot through which said rod passes and is fulcrumed, and means for rocking said arm; substantially as described.

11. In a sewing machine, a looper, an operating mechanism therefor including a universally pivoted rod, upon which the looper is supported, a rock shaft carrying a crank upon which one end of said rod is pivoted to swing in two directions, a crank upon the opposite end of said rock shaft, and connections between the latter and the driving shaft; substantially as described.

12. In a sewing machine, in combination with a reciprocating needle, and a looper, with means for causing it to engage the needle loop, and then carry a thread into position to be engaged by the needle in its next reciprocation, said looper being provided with a projection on its under side in rear of the position of the needle when engaging the looper thread and adapted to engage the looper thread after the looper passes through the needle loop on its way to the position, when the needle enters the looper loop; substantially as described.

13. In a sewing machine, the combination of a reciprocating needle, a looper with means for causing it to engage the needle loop and then carry a thread into position to be engaged by the needle in its next reciprocation, said looper being provided with a projection on its under side in rear of the position of the needle when engaging the looper thread and adapted to engage the looper thread after the looper passes through the needle loop on its way to the position where the needle enters the looper loop, said looper having also a recess on its under side in advance of the projection to afford a clearance way for the needle; substantially as described.

In testimony whereof I affix my signature, in presence of two witnesses.
